United States Patent Office

Des. 228,925

Patented Oct. 30, 1973

228,925

RELIGIOUS ORNAMENT

George M. Wallace, 64 Clinton St.,
Paterson, N.J. 07522

Filed June 19, 1972, Ser. No. 264,195

Term of patent 14 years

Int. Cl. D11—02

U.S. Cl. D29—23 A

The figure is a perspective view of a religious ornament showing my new design, the side opposite being identical thereto.

I claim:

The ornamental design for a religious ornament, as shown and described.
